UNITED STATES PATENT OFFICE.

EDWARD LOOMIS BOWES, OF KETTLE FALLS, WASHINGTON.

PAPER-FASTENER.

1,071,548.

Specification of Letters Patent. Patented Aug. 26, 1913.

Application filed November 21, 1912. Serial No. 732,631.

To all whom it may concern:

Be it known that I, EDWARD LOOMIS BOWES, a citizen of the United States, residing at Kettle Falls, in the county of Stevens and State of Washington, have invented a new and useful Improvement in Paper-Fasteners, of which the following is a specification.

My invention relates to certain new and 10 useful improvements in paper-fasteners, and is fully described and explained in the specification and shown in the accompanying drawings, in which:

Figure 1 is a perspective view showing 15 my device in one position of use; Fig. 2 is a similar view showing the device in another position, and Fig. 3 is a perspective view of the device itself.

The purpose of the present device is to 20 afford a separable ring, of the type which is frequently used in connection with notebooks and loose-leaf binders generally, which can be passed through a bundle of papers, as shown in Fig. 2, so that the papers are 25 free to be separated entirely while still on the ring, whereby the entire surface of each sheet can be inspected. Furthermore, if it be desired at any time to remove a single sheet, a bunch may be separated into two parts 30 at the top of which the sheet to be extracted lies and then by separating the ring, this single sheet can be taken out without disturbing the order of the other papers. This manner of operation is well known in connection 35 with loose-leaf binders of one sort and another, and it is, of course, desirable. However, there are frequently papers which it is desired to treat and handle in this manner, which it is also desired to hold together 40 in a solid flat bundle for filing, as by the use of the ordinary paper-clip of wire, and my principal object is to afford a single clip which will permit of both methods of handling the paper.

Referring to the drawings, 4 is a wire annulus having a pointed tip 5, and a recurved-end 6 forming an eye in which the pointed end can be engaged, as illustrated. The metal of the wire of the ring is continued back from this recurved-eye 6 in a part 7 parallel to and alongside of the ring 4, which recurved-part terminates in a radial projection 8.

When the device is used merely as a separable ring, as shown in Fig. 2, it is passed 55 through a hole previously prepared in the

bunch of papers or, if desired, the pointed end of the device will form its own hole. When the end of the ring is engaged with the eye 6, the papers are permanently fastened and may be turned over while preserving their order in the same way as if fastened with any ordinary separable-ring paper-fastener. However, when it is desired to hold the papers in a solid flat bunch for 60 filing, the plane of the ring is laid down flat against the bunch of papers, as shown in Fig. 1, and the recurved part 7 is placed on the opposite side of the bunch from the main annulus 4 and thereby the papers are 65 firmly gripped together. Of course, it will be obvious that the fastener can be pushed farther over the bunch than is shown in Fig. 1, by the pressure of the finger upon the 70 annulus in a direction to produce the result. The fastener shown in Fig. 1 is partially pushed onto the bunch of papers, in order that the construction and operation may be 75 most clearly understood.

There is thus provided a paper-fastener 80 which possesses all the advantages of the ordinary separable ring in that the entire surface of each sheet may be examined and the papers readily turned over from time to time or, if desired, separated for the removal 85 of single sheets, and at the same time all the advantages of firm binding in a compact, tight bunch are fully present. Furthermore, when the device is in place and the papers are arranged for filing, there are no 90 projections which in any way interfere with ready filing, nor does the device add materially to the size of the bunch of papers it contains.

I realize that considerable variation is 95 possible in the details of the present construction, without departing from the spirit of my invention, and by having described the same in detail, I do not intend to be limited thereto, except as pointed out in the 100 following claims, in which it is my intention to set forth all the novelty inherent in the construction described as broadly as may be permitted by the state of the art.

I claim as new and desire to secure by 105 Letters Patent:—

1. A fastener having a paper-receiving annulus adapted to be separated for the insertion and removal of sheets of paper, and a paper-clamping part adjacent thereto between which and the annulus papers may be placed, for the purpose set forth.

2. A fastener having a paper-receiving annulus adapted to be separated for the insertion and removal of sheets of paper, and a paper-clamping part adjacent and parallel thereto between which and the annulus papers may be placed, for the purpose set forth.
3. A fastener having a paper-receiving annulus adapted to be separated for the insertion and removal of sheets of paper, and an integral recurved paper-clamping part adjacent and parallel thereto between which and the annulus papers may be placed, for the purpose set forth.
- 10 4. A paper-fastener of wire having an open annulus, one end of which is recurved to form an eye adapted to receive one end of the wire, the recurved part being continued parallel to the annulus to form paper-clamping means.
- 15 5. A paper-fastener of wire having an open annulus, one end of which is pointed and the other of which is recurved to form an eye adapted to receive the pointed end, the recurved part being continued parallel 25 to the annulus to form paper-clamping means.
6. A paper-fastener of wire having an open annulus, one end of which is recurved to form an eye, the recurved part being continued parallel to the annulus to form paper-clamping means and terminating in an outward projection adapted to engage the eye.

In testimony whereof I have hereunto set 35
my hand this 2d day of November, 1912.

EDWARD LOOMIS BOWES.
